BY Alan M. Johnson, ATTORNEY

UNITED STATES PATENT OFFICE.

JOHN KARITZKY, OF GARWOOD, NEW JERSEY, ASSIGNOR TO HENRY E. NEWHALL, OF PLAINFIELD, NEW JERSEY.

NAIL FASTENER.

Application filed January 3, 1923. Serial No. 610,457.

To all whom it may concern:

Be it known that I, JOHN KARITZKY, a citizen of the United States, residing at Garwood, in the county of Union and State of New Jersey, have made certain new and useful Improvements in Nail Fasteners, of which the following is a specification, taken in connection with the accompanying drawings.

10 My invention relates to nail fasteners in which by merely driving the nail into the fastener, shield or expansion member the work is secured to the wall or other suitable support.

15 My invention more particularly relates to such a nail fastener in which the expansion member or shield is preferably formed from sheet metal and bent back upon itself to form two sides which are adapted to be forced apart by the nail as it is driven home.

20 My invention further covers such an expansion shield which is adapted to be expanded by the entering nail first in one direction, and then a portion of the shield or 25 expansion, is adapted to be expanded in a different direction, to obtain a firmer grip or bond between the expansion shield and the wall, ceiling or other support in which it is located.

25 My invention further relates to such a nail fastener which is provided with a weakened portion near the meeting ends of the sides, and which is adapted to cooperate with the end of the nail to obtain the second 30 expansion.

35 My invention further relates to certain articles of manufacture, combinations and sub-combinations and details of construction all of which will be more fully hereinafter described and pointed out in the claims.

40 In the drawing I have shown one embodiment of my invention, but it is of course to be understood that my invention is not to be confined to this embodiment shown by 45 way of illustration.

Fig. 1 is a plan view of a blank from which I preferably form my nail expansion shield;

Fig. 2 is a side elevation of the blank 50 with the ends bent at right angles to the central portion;

Fig. 3 is a cross section on the line 3—3 of Fig. 2;

Fig. 4 is a side elevation of the nail ex-

pansion or shield formed by bending the 55 blank back upon itself;

Fig. 5 is a side elevation, similar to Fig. 4, with the nail fastener or shield rotated 90°;

Fig. 6 is a horizontal section through a 60 wall or other suitable support showing the manner of inserting the nail fastener in a hole;

Fig. 7 is a vertical section of the same nail 65 fastener and nail;

Fig. 8 is a vertical section, similar to Fig. 7, showing the nail driven into the expansion or shield and after the shield has been expanded in different planes;

Fig. 9 is a horizontal section showing the 70 work supported by the nail rather than by the shield.

In the preferred form of my invention, I take a strip of metal 1, Fig. 1, which may be flat rolled steel, aluminum, brass, lead 75 or in fact any suitable metal, which can be shaped and bent. By any suitable means, either by hand or by a press, I provide this blank 1 with a weakened portion 2. This weakened portion may be variously formed; 80 preferably I provide the blank with a slot 3 which will weaken the part 2. I also preferably provide the ends of the blank with flanges or stops 4, 4. When this sheet metal blank 1 is bent back on itself on the line 5, 85 it forms an expansion shield 6, having the two sides 7, 7 and open at one end to receive the nail. I also preferably provide the sides 7, 7 with an interior curved surface 8 so as to more readily fit and conform to the cylindrical surface of the nail 9.

In use the nail expansion or shield 6 is placed within the hole or aperture 10 in the wall or other suitable support 11, as shown in Figs. 6 and 7. In these figures the 95 work 12 to be supported on the wall or other suitable support has a hole through which the shield or fastener 6 is passed until the flanges or stops 4, 4 contact with the exterior surface of the work. This of 100 course is simply one way in which the work may be supported, my invention not being limited to any particular way to support the work for it might be supported as shown in Fig. 9 wherein the work is supported 105 directly upon the nail rather than upon the shield or fastener.

As the nail 9 is driven into the shield or

fastener 6 by blows from a hammer upon the head 14, the two side arms 7, 7 of the fastener or shield will have an initial primary expansion away from each other in one direction. This expansion alone, in most cases, might be sufficient to support any ordinary work or load 12 for the particular size fastener used. To insure, however, an additional and tremendous grip or bond between the shield 6 and the wall of the hole 10, I have an additional and secondary expansion in a different direction from the first expansion. This may be done in various ways. I have shown for example the closed end 15 weakened in any suitable manner so that the wedge or conical point 16 of the nail 9 will cause that portion of the shield to expand in a different direction from the expansion of the side arms 7, 7. Preferably I accomplish this result by forming the shield 6 with the slot 3 which extends up each arm 7, 7 a short distance from the point 15. As the nail 9 is driven into the shield or fastener 6, and after the primary expansion due to forcing the side arms 7, 7 from each other, the end 16 of the nail will engage with the slot 3 of the shield or expansion and preferably pass through it as shown in Fig. 8, which will cause the portions 17, 17 of the side arms 7, 7 to be expanded in a different direction from the first or primary expansion. This secondary expansion is shown, somewhat exaggerated in Fig. 8.

It will be clear that my invention can be made from sheet metal and formed in a punch press at minimum expense; that a powerful grip or bond is obtained simply by driving the nail into the shield or expansion, and that this expansion occurs successively in two different planes.

Having thus described this invention in connection with an illustrative embodiment thereof, to the details of which I do not desire to be limited, what is claimed as new and what is desired to secure by Letters Patent is set forth in the appended claims.

What I claim is:

1. The combination of a nail fastener having two sides bent back on themselves to form a shield, said sides being adapted to be expanded in different directions, and a nail adapted to expand said sides first in one

direction and a portion of said sides in another direction as the nail is driven into the shield.

2. The combination of a nail fastener having two sides bent back on themselves to form a shield, said sides being provided with an expanding portion adjacent their meeting ends, said sides being adapted to be expanded in different directions, and a nail adapted to cooperate with said expandable portion and expand said sides first in one direction and a portion of said sides in another direction as the nail is driven into the shield.

3. The combination of a nail fastener having two sides bent back on themselves to form a shield, said sides being provided with a slot adjacent their meeting ends, said sides being adapted to be expanded in different directions, and a nail adapted to cooperate with said slot and expand said sides first in one direction and a portion of said sides in another direction as the nail is driven into the shield.

4. A new article of manufacture comprising a nail expansion shield formed from sheet metal bent back on itself midway of its length to form two sides of equal length, one end of the shield being open to receive a nail and the other end provided with weakening means to permit ready expansion of said end.

5. A new article of manufacture comprising a nail expansion shield formed from sheet metal bent back on itself midway of its length to form two sides of equal length, one end of the shield being open to receive a nail and the other end provided with a slot to permit ready expansion of said end by a nail.

6. The combination of a nail and an expansion shield formed from sheet metal bent back on itself midway of its length to form two sides of equal length, one end of the shield being open to receive a nail and the other end being adapted to be expanded by said nail in a different direction from the two sides.

JOHN KARITZKY.
